UNITED STATES PATENT OFFICE

FREDERICK A. BERG, OF CHICAGO, ILLINOIS

TOY AIRCRAFT LINER

Application filed March 10, 1938. Serial No. 260,673.

This invention relates to improvements in toy aircraft liners, and has for one of its principal objects the provision of a toy aircraft simulating an air-liner, such as is now used in the aerial transportation of passengers.

One of the important objects of this invention is to provide, in a toy aircraft liner, a plurality of seating positions, at least two of which are provided with control means for both steering and propelling the vehicle, thereby providing a dual control and driving mechanism which will be particularly interesting to the occupants of the device.

Another important object of the invention is the provision, in a toy aircraft liner, of a completely closed body provided with means for visibility both from the front and sides and also in the rear.

Another object of the invention is the provision, in a toy aircraft liner, of means for providing separate elements of ingress and egress for the various compartments.

Another and further important object of the invention is to provide, in a toy vehicle of the class described, a plurality of quasi-tractor, pusher and helicopter radial engines with associated propellers, all of which are positively operated when the device is in motion.

Still another important object of the invention is to provide, in combination with the dual control system, a novel means of steering and rear support for the device while at the same time the dual driving mechanism further accomplishes the simulation of an emergency landing gear.

Other and further important objects of the invention will be apparent from the disclosures in the accompanying drawings and following specification.

The invention, in a preferred form, is illustrated in the drawings and hereinafter more fully described.

In the drawings:

Figure 1 is a side elevation of the improved toy aircraft liner of this invention, parts being in section and parts being broken away.

Figure 2 is a top plan view of the toy liner.

certain portions being removed and other parts being shown in section.

Figure 3 is a sectional view taken on the line 3-3 of Figure 1 looking in the direction indicated by the arrows.

Figure 4 is a plan view of the rear supporting and steering dolly showing its associated parts.

Figure 5 is a detail view, partly in section, showing the construction and operation of the forward driving mechanism.

Figure 6 is a view showing the resilient support of the steering dolly, its mounting in the fuselage, and its association with the rudder.

Figure 7 is a detail view of the steering dolly, illustrating particularly the steering mechanism and its retaining means.

Figure 8 is a detail view of the demountable drive for the combination rotary engines and propellers, illustrating the means for simultaneously revolving the tractor, pusher, and helicopter propellers.

Figure 9 is a detail view of the same driving mechanism showing particularly the demountable feature comprising a separable driving shaft.

As shown in the drawings:

The reference numeral 10 indicates generally the fuselage or body of the improved toy aircraft liner of this invention, and it will be noted that the same is so shaped as to simulate the well-known aircraft used for transporting a plurality of passengers.

A removable top or hood 12 is provided on the toy liner, the same being formed in two sections hinged together as shown at 14, whereby the forward end may be raised with respect to the rear section, permitting ingress of a passenger or occupant to the forward compartment or section of the liner. A step 16 formed of a metal strap is provided for facilitating entry into this forward compartment.

Ingress to the rear compartment is obtained by means of a pair of doors 18 which are hinged as shown at 20, and each door is provided with a slideable window 22 of transparent material. Associated with the window is a rack 24 operated by means of a gear 26 which in turn is controlled by a handle 28

whereby the window 22 may be raised or lowered at will. Hingedly mounted directly beneath the door 18 is a fuselage door 30 mounted on hinges 32 and operating in the same plane as the door 18, this being fixed in the desired closed position by means of a manually operated latch 34. It will be evident that when the fuselage door 30 is closed, a dropping of the handle 28 into the lowermost position shown by the dotted lines in Figure 1 will operate as a latch to prevent opening of the upper portion 18 of this combination door unless both portions are opened at once.

The roof of the top 12 is preferably flat as shown, and the forward portion is built in a stream-line construction sloping downwardly to merge suitably with the substantially spherical stream-line cowl of the fuselage 10. A sloping transparent window 36 is positioned in the forward portion of the top 12, and in order to provide a proper support and also a protective element for this window, forwardly and downwardly extending brackets 38 are provided, the ends of which drop into suitable slots provided therefor in the cowl 10. It will be noted that behind the window 36 and the brackets 18 is positioned an integral portion 40 of the cowl which simulates the corresponding curved element of an aircraft.

A plurality of vents 42 are built into the top comprising gratings as shown, and provided for the purpose of ventilation and also for lookout ports. At the rear of the top 12 is provided a pair of downwardly and rearwardly extending latch members 44 which pass through corresponding openings in a cross strut 46 of the fuselage whereby the top is ordinarily retained in position. Latches or hooks 48 at the sides of the top co-operate with the elements 44 to retain the top in proper position. It will be obvious that the same can be readily removed if desired, the upper portions of the side doors being removable with the top. A rear vision window is also provided as shown at 50.

At the rear of the fuselage and directly behind the cross strut 46 is the empennage which in this instance comprises a compartment 52 covered by a pair of hinged lids 54 provided with a latching means 56. This will permit of the transportation of various small articles by the occupants of the device and also provides for the storage of tools or similar objects if desired.

At the rear of the empennage is a combination steering dolly 58 and rudder 60. The steering dolly comprises essentially a pair of wheels 62 mounted upon a cross axle 64 which in turn is supported by a bifurcated element 66, the same comprising a seat or receptacle for a bearing stem 68 which is preferably a metal rod square in cross section and which passes upwardly through the rear of the empennage 52. It will be noted that a helical

spring 70 surrounds the lower portion of the shaft 68 and rests upon the top of the member 66. This provides for a resilient supporting of the entire fuselage on the steering dolly. It will be noted that the upper end of the shaft 68 is fitted into an opening 72 in the rudder 60 and sufficient space is provided therein for the plunger movements of the shaft 66. A pin 73 (Figure 7) is passed transversely through the top of the shaft 68 in the space 72, and thereby operates to retain the shaft and the dolly in associated position with the aircraft.

Mounted on the shaft 66 at its lower end is a mutilated gear 74 which comprises part of the steering mechanism, the gear having at each end an opening 76 for the reception of a pin 78 which in turn locks to a shaft 80 extending forwardly to the dual steering elements as shown by the upwardly extending shafts or stems 82 and 83, each of which is pivotally mounted in the bottom of the fuselage 10. At the top of each of these steering shafts is a steering wheel 84 which is mounted to revolve freely thereon, the steering action being accomplished solely by a forward and rearward motion of the shafts 83 which in turn communicate a longitudinal motion to the rod 80. The steering shafts 82 and 83 are simultaneously operated by means of a communicating rod 81 which passes from one to the other adjoining lower ends and which is in alignment with the operating rod 80.

A metallic strip 85 surrounds the edges of the rudder 60 and is so connected at its lower forward end to the shaft 66 that any turning motion of the steering dolly is transmitted to the rudder 60, thereby simulating an actual steering motion of an aircraft liner in operation.

A plurality of elevators are associated with the empennage and the rudder as shown at 86. These elevators comprise two parallel horizontal wings 86 connected by vertical elements 87.

The driving mechanism comprises essentially a plurality of pairs of operating pedals as shown at 88 and 90, the pedals 88 being mounted on a crank shaft forming part of a speed increasing gear means which comprises an internal gear 92 which operates a pinion 93 which in turn is mounted on a shaft or axle 94 supporting the wheels 95. The outermost pair of the wheels 95 may be readily removed thereby providing a source of interesting work for the owner of the toy air liner.

Forming part of the crank shaft upon which the pedals 88 are mounted is a combined pulley 96 and a sprocket 97. The pulley drives a belt 98 which in turn operates the means for rotating the engines.

The sprocket 97 has operatively associated therewith a chain 99 which runs over a sim-

ilar sprocket 100 which in turn is mounted on a shaft 102 upon which the pedals 90 are positioned. A shield or guard 104 is positioned over the sprocket 100 and the chain 99 so as to prevent accidental contact of the clothing or limbs of the operators with the mechanism. The crank shaft 102 is itself maintained in position by means of downwardly extending supporting brackets 106 which are securely bolted to the fuselage 10, and these brackets form part of a system of supporting brackets, the remainder of which constitute similar elements 108 also bolted to the fuselage and extending downwardly to provide supports for the emergency landing wheels 110 which are free to rotate on the axles 112. The brackets 106 and 108 are transversely connected by a rod 114 which also serves as a foot rest.

The belt 98 operated by the pulley 96 extends upwardly and passes over a pulley 21 which in turn is mounted on a shaft 23 extending transversely across the fuselage and mounted in suitable bearings in the sides thereof.

As shown in Figure 9, this shaft 23 is provided at its outer ends with caps 25, each of which is notched for the reception of a cross pin 27 which is itself mounted in a removable or demountable shaft 29 at the other end of which is positioned a bevel gear 31. This bevel gear 31 operates a pair of gears 33 and 35, the gear 33 in turn being mounted upon a shaft 37 which extends longitudinally and operates tractor and pusher engines and propellers 39 and 41 respectively.

The gear 35 in turn is mounted to a shaft 141 which extends upwardly through the wing 43 and operates a helicopter rotary engine and propeller 45.

The wings 43 are themselves pivotally mounted at 47 to the fuselage and are adapted to be dropped downwardly when supporting rods 49 are released from suitable retaining sockets 51 mounted on the sides of the fuselage, as best shown in Figure 3.

It will be noted that the members 49 comprise U-shaped elements swingably mounted at the lower ends of the V-shaped supporting brackets 19, which themselves support the motors 39 and 41, these V-shaped elements 19 being in turn suitably anchored to the lower surface of the wings 43.

It will be evident that by this construction the device may be dismantled to a considerable extent so as to require a great deal less space when stored and not in use. This feature also provides an additional source of enjoyment for the users. In order to allow of a free movement of the shaft 29, and its associated gear 31 with respect to the mechanism comprising the gears 33 and 35 and the shafts 37 and 141, the end of the shaft 29 is mounted in a bearing comprising a bifurcated element as best shown at 53

in Figure 8 and is retained in suitable position by means of a locking washer 55. This allows of a free pivotal motion of the shaft 29 and the gear 31 with respect to the transverse shaft 37 allowing the shaft 29 to drop into the position indicated by the dotted lines at 29 in Figure 3 when the wing 43 is released. Obviously, the wings 43 with their associated elements may also be moved into raised position with respect to the fuselage especially when the top has been removed.

A continuation of the wings 43 extends across the body of the fuselage in the same plane as the outer ends of the wings and a portion of this wing as shown at 57 is fixed with respect to the body. The forward half of this wing portion, however, as best shown at 59 in Figure 2, is hinged by means of hinges 61 and is adapted for upward and rearward motion with respect to the fixed element 57 and may be let downwardly thereupon when the forward compartment is occupied, thereby providing room for the occupant while at the same time affording a desirable shelf for the storage of small articles.

As best shown in Figure 1, the seats are formed of cushions 63 mounted on notched rails 65, each of the cushions having at its lower side edges a pair of downwardly extending projections 67 which are adapted to fit into a corresponding pair of notches in the rail 65, so that the seats may be moved forwardly or rearwardly to accommodate children of different ages and sizes. It will be noted that the element 71 which forms a part of the support for the cushion 63 extends upwardly at the rear to provide a support for a back cushion 73 whereby the entire seat with its associated back rest may be adjusted as aforesaid. A further auxiliary cushion is provided at 75.

A transverse brace and supporting element 77 extends across the fuselage as shown in Figures 1 and 3, and upon the rear face of this board 77 is mounted a plurality of indicia 79 simulating instruments. It will be noted that the transverse support 77 which comprises the instrument board forms part of a combination brace strut and landing gear comprising metallic brackets 89 suitably connected by means of rivets and bolts.

Underneath the surface of each wing and at the end thereof is a navigation or pilot light 183 which are preferably of a red and green color respectively.

I am aware that many changes may be made and numerous details of construction varied throughout a wide range without departing from the principles of this invention, and I therefore do not purpose to limit the patent granted herein otherwise than as necessitated by the prior art.

I claim as my invention:

1. A toy aircraft liner, including in combination, a fuselage, supporting and steering

wheels for the fuselage simulating landing gear, and a dual control for the steering wheels, said supporting wheels having drive means for propelling the vehicle, and a tandem drive for the supporting wheels, together with a pair of compartments for the occupants of the vehicle, and hinged doors for one of said compartments together with a removable top for the vehicle, hinged means providing ingress and egress to the other of said compartments.

2. A toy aircraft liner, including in combination, a body, supporting and steering wheels on the body simulating landing gear, means for operating the supporting wheels to propel the vehicle, dummy engines and propellers rotatably mounted on the vehicle, and means connected with the vehicle-operating elements for rotating said engines and propellers.

3. A toy aircraft liner, including in combination, a body, supporting and steering wheels on the body simulating landing gear, means for operating the supporting wheels to propel the vehicle, dummy engines and propellers rotatably mounted on the vehicle, and means connected with the vehicle-operating elements for rotating said engines and propellers, said means comprising a system of pulleys, belts, shafts and gears.

4. A toy aircraft liner, including in combination, a body, supporting and steering wheels on the body simulating landing gear, means for operating the supporting wheels to propel the vehicle, dummy engines and propellers rotatably mounted on the vehicle, and means connected with the vehicle-operating elements for rotating said engines and propellers, said means comprising a system of pulleys, belts, shafts and gears, certain of said shafts including demountable connections along their lengths.

5. A toy aircraft liner, including in combination, a body, foldable wings on the body, dummy engines and propellers rotatably mounted on the wings, driving means for the vehicle, said driving means including elements for operating the dummy engines and propellers, and demountable connections in the said driving means to permit of the disconnecting of same from the dummy engines upon the folding of the wings.

6. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments.

7. A toy aircraft liner, including a body, foldable wings on the body, combined supporting and propelling wheels for the body, and steering wheels for the body, a dual drive

for the propelling wheels, a dual control for the steering wheels, a pair of compartments for the occupants, doors for one of said compartments, and a hinged top for the other of said compartments, together with a storage compartment at the rear of the body.

8. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle.

9. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle, the propelling means for the vehicle comprising a pedal-operated internal gear in mesh with a pinion attached to the supporting wheels.

10. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle, the propelling means for the vehicle comprising a pedal-operated internal gear in mesh with a pinion attached to the supporting wheels, a pedal and sprocket drive positioned forward of the propelling wheels, and a sprocket and chain connection from the last-named drive to the internal gear drive.

11. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle, the propelling means for the vehicle comprising a pedal-operated internal gear in mesh with a pinion attached to the supporting wheels, a pedal and sprocket drive positioned forward of the propelling wheels, and a sprocket and chain connection from the last-named drive to the internal gear drive.

named drive to the internal gear drive, said pedal and sprocket drive positioned adjacent an additional pair of wheels simulating an emergency landing gear.

5 12. A toy aircraft liner, including a body, foldable wings on the body, combined supporting and propelling wheels for the body, and steering wheels for the body, a dual drive for the propelling wheels, a dual control 70 for the steering wheels, dummy engines and propellers rotatably mounted on the folding wings and an operating means for the said engines and propellers demountably connected to the propelling means for the vehicle, the 10 propelling means for the vehicle comprising a pedal-operated internal gear in mesh with a pinion attached to the supporting wheels, the connection between the propelling wheels and the dummy engine operating 15 means comprising a belt and pulley, a shaft driven by the pulley, said shaft having its ends mounted in bearings in the fuselage and projecting beyond the sides of the fuselage, a shaft and gear connection for the engines 20 and propellers, said shaft and gear connections pivotally mounted on the wing.

25 13. A toy aircraft liner, including a body, foldable wings on the body, combined supporting and propelling wheels for the body, and steering wheels for the body, a dual drive 75 for the propelling wheels, a dual control for the steering wheels, dummy engines and propellers rotatably mounted on the folding wings and an operating means for the said 80 engines and propellers demountably connected to the propelling means for the vehicle, the propelling means for the vehicle comprising a pedal-operated internal gear in mesh with a pinion attached to the supporting 85 wheels, and a sprocket and chain connection from the last-named drive to the internal gear drive, together with a protective 90 shield positioned over the driving chain.

40 14. A toy aircraft liner, including a body, foldable wings on the body, combined supporting and propelling wheels for the body, and steering wheels for the body, a tandem 95 drive for the propelling wheels, and a dual control for the steering wheels, together with navigation lights on the ends of the wings, one of said lights being green and the other 100 red, and each of the lights being positioned 105 beneath a wing.

45 15. A toy aircraft liner, including a body, foldable wings on the body, combined supporting and propelling wheels for the body, and steering wheels for the body, a dual 110

drive for the propelling wheels, a dual control for the steering wheels, a pair of compartments for the occupants, doors for one of said compartments, and a hinged top for the other of said compartments, together 70 with a storage compartment at the rear of the body, and a plurality of combination vents and lookout ports in the body.

16. A toy aircraft liner, including a body, foldable wings on the body, combined supporting and propelling wheels for the body, and steering wheels for the body, a dual drive for the propelling wheels, a dual control for the steering wheels, a pair of compartments for the occupants, doors for one 80 of said compartments, and a hinged top for the other of said compartments, together with a storage compartment at the rear of the body, and a plurality of combination vents and lookout ports in the body, two of 85 said vents being in the top of the body, one for each compartment and one of the vents positioned at the rear of the rear compartment.

17. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle, the propelling means for the vehicle comprising a pedal-operated internal gear in mesh with a pinion attached to the supporting 100 wheels, and a sprocket and chain connection from the last-named drive to the internal gear drive, together with a protective 105 shield positioned over the driving chain.

18. A toy aircraft liner, including in combination, a fuselage, supporting and steering wheels for the fuselage simulating landing gear, and a dual control for the steering wheels, and an instrument board in the fuselage.

19. A toy aircraft liner, including in combination, a fuselage, supporting and steering wheels for the fuselage simulating landing gear, and a dual control for the steering wheels, and a plurality of instrument boards in the fuselage, said instrument boards positioned on, and forming part of, brace members for the fuselage.

20. A toy aircraft liner, including in combination, a fuselage, supporting and steering wheels for the fuselage simulating landing gear, and a dual control for the steering wheels, said supporting wheels having drive 125 means for propelling the vehicle, and a tandem drive for the supporting wheels, together with a pair of compartments for the occupants of the vehicle, a pair of wings for the liner, said wings foldable against the 130

- sides thereof, the wings being positioned in one plane and having connecting portions extending across the fuselage, the forward part of said connecting portion being hinged-
5 ly mounted for upward and rearward motion to provide additional space for the occupant of the forward compartment.
21. A toy aircraft liner, including in combination, a fuselage, supporting and steering wheels for the fuselage simulating landing gear, and a dual control for the steering wheels, together with a pair of wings hinged-
10 ly connected to the sides of the body, and foldable for compactness, dummy engines mounted on the wings and V-shaped brackets supporting said engines.
22. A toy aircraft liner, including in combination, a fuselage, supporting and steering wheels for the fuselage simulating landing gear, and a dual control for the steering wheels, together with a pair of wings hinged-
15 ly connected to the sides of the body, and foldable for compactness, dummy engines mounted on the wings and V-shaped brackets supporting said engines,
- 25 supporting said engines, together with U-shaped brackets positioned transversely to the planes of the V-shaped brackets for removably supporting the wings in extended position.
- 30 23. A toy aircraft liner, including a body, foldable wings on the body, combined supporting and propelling wheels for the body, and steering wheels for the body, a dual drive for the propelling wheels, a dual control for the steering wheels, dummy engines and propellers rotatably mounted on the folding wings and an operating means for the said engines and propellers demountably connected to the propelling means for the vehicle, the propelling means for the vehicle a pedal-operated internal gear in mesh with a pinion attached to the supporting wheels, a pedal and sprocket drive positioned forward of the propelling wheels, and a sprocket and chain connection from the last-named drive to the internal gear drive, said pedal and sprocket drive positioned adjacent an independent additional pair of wheels simulating an emergency landing gear.
- 40 24. A toy aircraft liner, including in combination, a fuselage, supporting and steering wheels for the fuselage simulating landing gear, and a dual control for the steering wheels, said supporting wheels having drive means for propelling the vehicle, and a tandem drive for the supporting wheels, together with a pair of compartments for the occupants of the vehicle, and an adjustable seat in each compartment, said adjustable seat comprising a seat cushion and a back rest integral therewith.
- 50 25. A toy aircraft liner, including in combination, a fuselage, supporting and steering wheels for the fuselage simulating landing gear, and a dual control for the steering
- wheels, together with a rudder mounted on the steering wheels and movable therewith, and a resilient hinged connection between the steering wheels and the fuselage, said connection including a dolly, a square shaft vertically positioned on the dolly, brackets at the rear of the fuselage for rotatably and slidably supporting the shaft, a steering element fixedly mounted on the shaft.
26. A toy aircraft liner, including in combination, a fuselage, supporting and steering wheels for the fuselage simulating landing gear, and a dual control for the steering wheels, together with a rudder mounted on the steering wheels and movable therewith, and a resilient hinged connection between the steering wheels and the fuselage, said connection including a dolly, a square shaft vertically positioned on the dolly, brackets at the rear of the fuselage for rotatably and slidably supporting the shaft, a steering element fixedly mounted on the shaft, and a relatively fixed connection between the rudder and the said shaft.
27. A toy aircraft liner, including in combination, a fuselage, supporting and steering wheels for the fuselage simulating landing gear, and a dual control for the steering wheels, together with a pair of wings hinged-
35 ly connected to the sides of the body, and foldable for compactness, dummy engines mounted on the wings and V-shaped brackets supporting said engines, together with swingingly mounted U-shaped brackets positioned transversely to the planes of the V-shaped brackets for removably supporting the wings in extended position.
28. A toy aircraft liner, including in combination, a fuselage, supporting and steering wheels for the fuselage simulating landing gear, and a dual control for the steering wheels, together with a pair of wings hinged-
40 ly connected to the sides of the body, and foldable for compactness, dummy engines mounted on the wings and V-shaped brackets supporting said engines, together with swingingly mounted U-shaped brackets positioned transversely to the planes of the V-shaped brackets for removably supporting the wings in extended position, and sockets on the sides of the fuselage for the removable reception of the lower ends of the U-shaped brackets.
29. A toy aircraft liner, including in combination, a fuselage, supporting and steering wheels for the fuselage simulating landing gear, and a dual control for the steering wheels, said supporting wheels having drive means for propelling the vehicle, and a tandem drive for the supporting wheels, together with a pair of compartments for the occupants of the vehicle, and a foot rest at the forward portion of the fuselage for the occupant of the front compartment.
30. A toy aircraft liner, including in combination, a fuselage, supporting and steering

wheels for the fuselage simulating landing gear, and a dual control for the steering wheels, said supporting wheels having drive means for propelling the vehicle, and a tandem drive for the supporting wheels, together with a pair of compartments for the occupants of the vehicle, and a foot rest at the forward portion of the fuselage for the occupant of the front compartment, said foot rest forming part of the simulated landing gear.

31. A toy aircraft liner, including in combination, a fuselage, supporting and steering wheels for the fuselage simulating landing gear, and a dual control for the steering wheels, together with a pair of wings hingedly connected to the sides of the body, and foldable for compactness, and a shelf extending across the interior of the fuselage in the same plane as the wings.

32. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion.

33. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion, separately and jointly operated.

34. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion, separately and jointly operated, and a window in the upper portion of each door.

35. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion, separately and jointly operated, and a win-

dow in the upper portion of each door, together with means for raising and lowering the window.

36. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion, separately and jointly operated, and a window in the upper portion of each door, together with means for raising and lowering the window, said means comprising a pinion and rack, and a handle for operating the pinion.

37. A toy aircraft liner, including a body, foldable wings on the body, combined supporting and propelling wheels for the body, and steering wheels for the body, a tandem drive for the propelling wheels, a dual control for the steering wheels, a pair of compartments for the occupants, doors for one of said compartments, and a hinged top for the other of said compartments, each of said doors comprising an upper and a lower portion, separately and jointly operated, and a window in the upper portion of each door, together with means for raising and lowering the window, said means comprising a pinion and rack, and a handle for operating the pinion, said handle when positioned downwardly acting as a latch for the upper portion of the door with respect to the lower portion.

In testimony whereof I affix my signature.

FREDERICK A. BERG.
